UNITED STATES PATENT OFFICE.

JAMES M. KISSINGER AND SAMUEL H. J. HEFFNER, OF POTTSVILLE, PENNSYLVANIA.

FENCE-POST.

1,024,858.

Specification of Letters Patent. Patented Apr. 30, 1912.

Application filed December 6, 1911. Serial No. 664,298.

To all whom it may concern:

Be it known that we, JAMES M. KISSINGER and SAMUEL H. J. HEFFNER, citizens of the United States, residing at Pottsville, in the 5 county of Schuylkill and State of Pennsylvania, have invented certain new and useful Improvements in Fence-Posts, of which the following is a specification.

The present invention relates to certain 10 new and useful improvements in fence posts, and has for its object to provide a post which embodies novel features of construction whereby it can be used with equal facility in connection with a wire fence, a 15 picket fence, or a rail fence, as may be desired.

A further object of the invention is to provide a post of this character which is simple and inexpensive in its construction, 20 which can be employed in connection with various base members according to the nature of the soil or the ideas of the person erecting the fence, and which is strong and durable in its design.

25 With these and other objects in view, the invention consists in certain novel combinations and arrangements of the parts as will more fully appear as the description proceeds, the novel features thereof being 30 pointed out in the appended claims.

For a full understanding of the invention, reference is to be had to the following description and accompanying drawings in which:—

35 Figure 1 is a perspective view of a fence post constructed in accordance with the invention. Fig. 2 is a transverse sectional view on the line 2—2 of Fig. 1. Fig. 3 is a vertical transverse sectional view through 40 the lower portion of the post. Fig. 4 is a side elevation of a slightly modified construction of the post. Fig. 5 is a transverse sectional view through one of the base members, on the line 5—5 of Fig. 4, and Fig. 6 is 45 a perspective view of the lower end of a post, showing a further form of base member which may be employed.

Corresponding and like parts are referred to in the following description and indicated 50 in all the views of the drawings by the same reference characters.

Specifically describing the present embodiment of the invention, the numerals 1 and 2 designate two plates or strips of sheet 55 metal which constitute the body portion of the post and have a spaced and parallel re-

lation to each other. A strip 3 of wood or similar material is interposed between the plates 1 and 2 at one of the edges thereof, suitable fastening members 4 being provided 60 which extend through the plates and the wood strip. At the opposite side of the post, the edges of the strips 1 and 2 are connected by bolts or fastening members 5, spacing sleeves 6 being arranged upon the 65 bolts and interposed between the plates so as to hold the plates in a proper spaced relation. The plate 1 has a series of openings 7 therein, and the plate 2 is formed with corresponding openings 8. In forming the 70 openings 8, however, the metal is only cut at the top and sides of the opening, tongues 9 being thereby provided which are adapted to be bent inwardly, as shown more clearly in Fig. 3, so as to span the space between 75 the plates and rest upon the lower edges of the openings 7.

When the post is used for a rail fence, the rails 10 which are shown by dot and dash lines in Figs. 1 and 3 are inserted through 80 the openings 7 and 8 and rest upon the tongues 9. These tongues form a large bearing or seat for the rails so that the same are not cut and injured by the sharp lower 85 edges of the openings in the plates.

When the post is used for a wire fence, the wire strands are secured to the wooden strip 3 by suitable fastening members such as the staples 11. These staples 11 may be 90 spaced as found necessary, and provide a ready and convenient means for securing the wires in position.

Should it be desired to use the post with a picket fence, the slightly modified construction shown in Fig. 4 would be employed. In this particular instance, the plates 1 and 2 of the post are only provided with two sets of the openings 7 and 8, the said openings being located at the top and bottom thereof. The horizontal post rails 100 would be inserted through these openings, and the vertical pickets could be secured to these horizontal rails in the usual manner.

The post is adapted to be used with numerous forms of bases, each of which comprises a pair of plates 12 of a width corresponding to the width of the plates 1 and 2. These base plates 12 are provided toward their upper ends with the transverse ribs 13 which bear against the lower ends of the 110 plates 1 and 2, the upper ends of the plates 12 fitting against the inner faces of the

plates 1 and 2 and being secured thereto by means of the bolts 14. A transversely disposed spacing strip 15 is arranged between the upper ends of the base plates 12, the 5 ends of the said spacing strip being rolled around the bolts 14, as indicated more clearly in Fig. 4. This spacing strip 15 together with the rolled ends thereof serves to hold the upper ends of the base plates 12 10 firmly against the plates 1 and 2 of the post, so as to provide a rigid construction.

In Figs. 1 and 3, the base plates 12 are shown as diverging downwardly and having the lower corners thereof bent inwardly 15 at 17 so as to provide wings adapted to engage the soil.

In Fig. 4, the plates 12 are provided in opposite edges thereof and at a point slightly below the shoulders 13 with trans- 20 verse slits or cuts 18, the edges of the plates below the cuts being curved inwardly at 19.

A further modification of the base plates 12 is shown in Fig. 6, in which the opposite edges of the base plates are cut away as indicated at 20, the lower ends of the base plates having the edges thereof curved inwardly toward each other at 21. It will be obvious that these base plates may be shaped and cut in various manners without departing in any way from the spirit 30 of the invention.

It will also be obvious that, as previously described, the post may be employed with equal facility either in connection with wire 35 fences, rail fences, or picket fences.

Having thus described the invention, what we claim as new and desire to secure by Letters Patent, is:—

1. A fence post including a pair of spaced 40 plates formed with corresponding openings adapted to receive fence rails, a longitudinal strip of wood interposed between the plates at one side thereof, fastening members connecting the plates, and a base applied to the lower ends of the plates.

2. A post including a pair of spaced plates having corresponding openings 50 therein adapted to receive fence rails, connecting members between the plates, seats connecting the lower edges of the openings in the plates and serving as a rest for the rails, and a base applied to the lower ends of the plates.

3. A fence post including a pair of

spaced plates having corresponding openings formed therein for the reception of fence rails, tongues projecting from the lower edges of the openings of one of the plates and extending across to the lower edge of the corresponding openings in the 60 opposite plate to provide seats for the fence rails, connecting means between the plates, and a base applied to the lower ends of the plates.

4. A fence post including a pair of spaced 65 plates having corresponding openings formed therein for the reception of fence rails, one of the plates being formed with tongues which project from the lower edge of the openings therein and extend 70 across to the lower edge of the openings in the opposite plate to provide seats for the fence rails, a longitudinal strip of wood interposed between the plates at one side of the post, fastening members connecting 75 the plates, and a base applied to the lower ends of the plates.

5. A fence post including a pair of spaced plates having corresponding openings 80 therein for the reception of fence rails, one of the plates being formed with tongues projecting from the lower edges of the openings therein and extending across the space between the plates to the lower edges 85 of the corresponding openings in the opposite plate, the said tongues forming rests for the rails, a longitudinal strip of wood interposed between the plates at one side of the post, bolts connecting the plates at the opposite side of the post, spacing sleeves 90 applied to the bolts and interposed between the plates, and a base applied to the lower ends of the plates.

6. A fence post including a pair of spaced plates having corresponding openings 95 therein adapted to receive rails, a strip of wood interposed between the plates at one side of the post, wire engaging members applied to the said strip, and fastening members connecting the members at the opposite side of the post.

In testimony whereof we affix our signatures in presence of two witnesses.

JAMES M. KISSINGER.
SAMUEL H. J. HEFFNER.
